RESIDUUM COKING AND CRACKING

James W. Brown, Elizabeth, and Charles E. Jahnig, Red Bank, N. J., assignors to Standard Oil Development Company, a corporation of Delaware

Application June 9, 1951, Serial No. 230,746

5 Claims. (Cl. 196—49)

1 This invention relates to a method for coking and cracking heavy residual stocks. It relates particularly to a method wherein ash and coke forming constituents of a heavy residuum feed are first removed from the feed by being deposited on particles of fluidized inert solids, preferably coke, under conditions conducive to a minimum conversion of the feed to lighter hydrocarbons, while overall conversion of the feed is primarily accomplished thereafter in a catalytic manner. Specifically, the vapors resulting from the coking zone are passed to a cracking zone containing a bed of fluidized catalyst which is subsequently regenerated by combustion of the carbonaceous deposit. A characteristic feature of the invention is that the heat requirements of the coking zone as well as the catalytic cracking zone are supplied by direct mixing of hot regenerated catalyst with the inert solids in a mixing zone, whereupon catalyst and reheated inerts are segregated prior to being separately recycled to the appropriate conversion zones.

Various combinations of fluid coking and cracking steps have been proposed elsewhere. However, such processes have not been commercially attractive in view of the great heat requirements involved, especially since it has been assumed in the past that products from coking would be condensed and fractionated to provide a feed cut which had to be revaporized in the 30 catalytic cracking step. The heat requirements of the coking zone were usually supplied by means of a furnace from which heat was transferred indirectly to the coking zone, or by a continual feeding of a heat carrying medium such as coke particles directly into the coking zone. In such cases, however, the heat was originally obtained by combustion of at least a part of the net coke produced in the process or by combustion of similarly valuable extraneous fuels such as fuel gas. In still other known fluid coking processes, coke and a cracking catalyst or inert inorganic solids were mixed in the conversion zone for various purposes, such as to obtain a scouring action on the reactor walls, or to improve the 40 quantity and quality of the distillate product, but this invariably resulted in an excessive loss of catalyst by embedding in the coke, which also resulted in an undesirable contamination of the coke product by the added solids. On the other hand the catalyst itself became badly contaminated by the ash constituents of the heavy hydrocarbon feed in such mixed coking and catalytic cracking operations, and the quality of the desired product was generally inferior

2 to that obtained in the more common types of catalytic conversion. Also, the investment costs in the previous process has been undesirably high.

5 It is the main object of the present invention to avoid the aforementioned disadvantages by designing a process requiring a minimum number of vessels, having a more economical heat balance, a minimum of coke and catalyst contamination, and a maximum yield of high quality motor fuel fractions. Other objects will be apparent from the subsequent description of the novel process which comprises essentially a low temperature, low conversion coking step wherein 10 a heavy hydrocarbon feed is contacted with hot seed coke particles, preferably in a dense fluid bed, followed by a cracking step wherein the resulting hydrocarbon vapors are contacted with 15 a dense fluid bed of a cracking catalyst having a particle size distribution substantially different from the particle size distribution of the seed coke, a catalyst regeneration step wherein the carbonaceous deposit formed around the catalyst particles in the cracking step is burned off while in a dense fluid phase, a heat exchange 20 step wherein the hot regenerated catalyst is mixed with coke particles withdrawn from the coking zone, and a separation step wherein the resulting mixture of solids is separated by elutriation or the like into its two principal components, the catalyst being returned to the catalytic cracking zone and the reheated coke to the coking zone. Moreover, a preferred feature 25 of the invention involves multi-stage drying of the seed coke withdrawn from the coking zone so as to minimize adhesion of the catalyst to the coke particles when admixed therewith.

Having set forth the main objects and general nature of the invention, the latter is further illustrated by several specific examples wherein reference is made to the accompanying drawing.

Fig. 1 is a semi-diagrammatic illustration of a system suitable for carrying out one preferred embodiment of the invention, according to which 40 the cracking zone containing a dense bed of relatively fine cracking catalyst as well as a plurality of coking zones containing dense beds of relatively coarse coke are superimposed over each other in a single reactor and according to which 45 hydrocarbon feed is injected into the uppermost coke bed from which the resulting hydrocarbon vapors are passed upward to the catalytic cracking zone, whereas the coke particles are 50 passed downward into at least one other coking zone wherein the coke particles are dried prior

3

to mixing with hot regenerated catalyst in a separate mixing and elutriation zone whence re-heated coke particles are returned to the coking zones and regenerated catalyst is returned to the catalytic cracking zone;

Fig. 2 illustrates an alternative modification of the invention, according to which the catalytic cracking zone is superimposed on the coking zone in the same vessel which also contains the mixing-and-elutriation zone in direct communication with the coking zone; and finally

Fig. 3 illustrates a third alternative according to which low temperature coking of the hydrocarbon feed is essentially completed in a transfer line wherein the feed is mixed with hot coke particles prior to admission to the catalytic cracking zone wherefrom relatively fine catalyst is entrained overhead with the product vapors and passed to a combustion regenerator for eventual recycling to the cracking zone whereas the relatively coarse coke is withdrawn at the bottom and mixed with further amounts of hydrocarbon feed.

Referring now in detail to Fig. 1 of the drawing, reduced crude such as an 8% bottoms fraction of about 10-30 Conradson carbon, of about 5° API gravity and obtained from the vacuum distillation of a West Texas crude or a similar heavy residue is supplied to coking zone 2 through line 1 as a liquid at a temperature of about 300 to 300° F., or preferably at about 700° F. Inert solids, preferably petroleum coke particles having a particle size in the range between about 100 and 500 microns are maintained in the coking zone at a temperature of about 850° F. to 950° F. as a dense, turbulent, fluidized bed 3 having an upper level 4 and an apparent density of about 10 to 50 lbs./cu. ft. with densities of about 0.01 to 5 lbs./cu. ft. above level 4, while an inert gas such as steam introduced through lines 30, 31 and 32 as later described is being passed upwardly through the coke particles at a linear superficial velocity of about 0.5 to 5 feet per second.

The vapors produced in the hot coking zone 2 are passed therefrom through perforated plate 5 into the superimposed catalytic cracking zone 6 maintained at about 900° F. to 1000° F. and containing a dense, turbulent, fluidized bed 7 of a cracking catalyst such as one of the known synthetic silica-alumina composites. The physical characteristics of catalyst bed 7 are essentially similar to those of the coke bed 3 described above, except that the catalyst particle size is within the range of about 50 to 150 microns and is preferably at least 20 to 50 microns smaller than the smallest particles constituting a substantial portion of the coke in bed 3, so as to assure an efficient separation of the two solids in the subsequent elutriation. Thus, for instance, when coke ranging in size down to about 100 microns is used in the coker, the catalyst particles are preferably in the range between 20 and 50 or 80 microns, but when the coke particles of the process range in size between about 200 and 300 microns, catalyst particles in the range up to about 150 microns may be used. The cracked hydrocarbon vapors are withdrawn from cracking zone 6 through cyclone 8 or other gas-solid separator means and passed through line 9 to a conventional finishing system for recovery of naphtha, gas oil and other desired hydrocarbon fractions.

Spent catalyst is withdrawn from bed 1 through standpipe 10, which may have taps 11 and 12.

4

for admitting a small amount of an aeration gas, and the withdrawn catalyst is finally mixed with air admitted through line 12 and passed to regenerator 13 where carbonaceous deposits are burned off the catalyst in fluid phase at a temperature of about 1100° F. to 1250° F. in a manner well known per se. Excess heat may be removed from the system by means of heat exchanger 14 and hot regenerated catalyst is used to supply the heat requirements of the coking zones as well as the catalytic cracking zones in the manner described later herein. Moreover, especially where exchanger 14 is intended for preheating feed and thus supplying a portion of the regeneration heat directly to the coker, it may be necessary to locate the exchanger in a separate vessel through which hot catalyst is circulated. This allows greater flexibility and control over regeneration temperature without causing undue coking of feed within the heat exchanger, as might otherwise be the case if regenerator temperature permitted only a low feed circulation rate through the exchanger when immersed directly in the regenerator bed as shown in Fig. 1.

Coke from bed 3 of the coking zone is withdrawn through downcomer 15 to another stage 16 where the coke is again maintained as a dense, turbulent, fluidized bed 17 and where any unconverted, oily residuum which may be adhering to some of the coke particles is cracked and converted into vapors and dry coke. The second and any further consecutive stages are preferably at a higher temperature than the main coking zone, e. g. at 1000° F., but a substantial advantage is obtained even when all stages are at the same temperature as the main coking zone 2, since the main purpose of such staging is the prevention of oil soaked, incompletely coked particles leaving the coker bed in the coke portion withdrawn to the mixer as later described, which portion is a fairly representative sample of the particle mixture present in the particular bed.

For example, where only a one-stage coker is used, 22% of the coke withdrawn therefrom will have a residence time equal to less than 25% of the average or nominal holdup time, and such particles usually exhibit a considerable degree of stickiness. But, by using a 2-stage or even a 3-stage coker, the percentage of particles being withdrawn from the last stage having a residence time equal to less than 25% of the average total holdup is reduced drastically to 10 and 4%, respectively, and consequently the stickiness of the resulting coke product is materially decreased.

Net coke product may be withdrawn from the last bed 17 through pipe 18, it being particularly desirable to remove those coke particles which have grown too large for good fluidization in the system. Control of the coke particle size in the system can be achieved by screening out the largest coke particles while recycling the smaller ones, or the withdrawn particles may even be ground before being returned to the system. However, where grinding is employed, it is desirable to remove also the fines from the coke to be returned, as otherwise such coke fines would eventually become mixed with the catalyst and undesirably increase the necessary amount of carbon burning capacity.

A side stream of the coke from the dry coke bed 17 is withdrawn through line 19 to mixer-elutriator 20 where the coke particles are mixed

with hot catalyst particles withdrawn from regenerator 13 through line 21 while an inert gas such as steam is introduced into the bottom of vessel 20 through line 22 at a rate corresponding approximately to the minimum fluidization velocity for the coke particles, i. e. to give a linear superficial velocity of about 0.1 to 1 foot per second. As the two solids become mixed in vessel 20, they exchange heat so that the catalyst is cooled and the coke heated to about 1100° F. and moreover, due to the previously described difference in particle size, the relatively fine catalyst is stripped from the fluidized mixture in vessel 20 and entrained to the catalyst bed 1 in reaction zone 3, thereby supplying the heat required by the catalytic conversion step.

Coarse coke particles, essentially free of catalyst and reheated by contact with the regenerated catalyst, are withdrawn from mixing vessel 20 through standpipe 23 and after admixing with steam from line 30 are returned as a disperse suspension through lines 31 and 32 to coke beds 17 and 3, respectively, thereby supplying the necessary heat to the coking reactor. Moreover, especially where a relatively active coke product or a coke of lower volatile content is desired and where the process produces heat in excess of its other requirements, it may be preferable to remove net coke product from the process by way of the hot mixing vessel 20 and standpipe 24 rather than by way of the somewhat cooler coke bed 17 and pipe 18 described earlier herein.

Referring to Fig. 2, the modification illustrated therein accomplishes the purposes of the invention in a manner which differs somewhat from the embodiment previously described in that an appreciable amount of initial coking takes place in a transfer line, and in that the mixing-elutriation zone is directly in the main reactor and consequently requires a high pressure-drop grid between the coking zone and the superimposed catalytic conversion zone so as to permit upward flow of catalyst from the elutriator to the catalyst bed in the conversion zone.

In operating this system, the heavy hydrocarbon feed preheated to about 700° F. is introduced through line 101 and heated to about 800 to 1100° F. by mixing with coke particles withdrawn through standpipe 102 from mixing zone 103 later to be described. The coke particles preferably range in size from about 100 to 300 microns. The resulting suspension of coke in hydrocarbon feed, and steam introduced through line 101a is then passed upwardly through transfer line 104 at a rate of about 15 to 50 feet per second, equivalent to a transfer line residence of about 0.5 to 5 seconds, into the coking section 105 where the coke particles are maintained above perforated distributor plate 106 as a dense, turbulent, fluidized bed 107 having an apparent density of about 30 lbs./cu. ft. and having an upper level 108.

In this manner good mixing of the oil feed and coke is obtained whereby the oil is dispersed uniformly over the coke particles and partially coked with only a minimum formation of thermally cracked naphtha. After this first-stage coking in the transfer line, coking of the feed is completed in the coker bed 107 where any coke particles containing a surface film of incompletely coked feed have a chance to dry out before being withdrawn. The amount of coke yield is a function of the Conradson carbon value of the feed, which apparently represents asphaltenes and similar compounds convertible to coke even under the

mildest cracking conditions. After passage through coke bed 107 the hydrocarbon vapors liberated in the coking steps pass overhead from coking section 105 through a distribution grid 110 into cracking section 109 which is superimposed on the coking section 105 within the self-contained reactor vessel R, which, as will be later described, additionally contains a mixing section 111 below the cracking section 109 and next to coking section 105.

In the cracking section the hydrocarbon vapors flow up through the dense, turbulent, fluidized bed of cracking catalyst 112 at about 900° F.-1000° F. and finally through a dust separator 113 and line 114 to conventional product recovery facilities. Spent catalyst is stripped with steam in zone 128 in the usual manner, and goes through line 115 to the regenerator 116 where the carbonaceous deposit is removed from the fluidized catalyst by combustion. Air is blown into the regenerator through line 117 and distributor grid 118 and where necessary, through an auxiliary burner 119 in which extraneous fuel supplied through line 120 may be burned at a rate sufficient to supply the required heat to the system. Flue gases are removed from the regenerator through dust separator 121 and line 122.

The regenerated catalyst at about 1100-1200° F. is returned through line 123 and reactor wall opening 124 to the segregated mixing section 111 in the reactor where it mixes with a circulating coke stream withdrawn from the coker bed 107 through wall opening 125 which is located at a level intermediate between the catalyst inlet 124 and the fluid coke level 108 of the coker. The coke stream and the regenerated catalyst streams are currently mixed in mixing section 111 in a weight ratio ranging between about 0.2 and 3. Steam is injected through line 129 at the bottom of the mixing section 111 at a rate to give an upward gas velocity in the mixing section between about 0.1 and 1.0 feet per second so that the relatively finely divided cracking catalyst is elutriated and entrained upward from the catalyst-coke mixture while the coke particles are fluidized but are not substantially entrained overhead.

The regenerated catalyst is thus carried into the cracking section 109 where it again becomes part of the fluid catalyst bed 112 while supplying the necessary heat of reaction thereto. In some cases it may be desirable to bypass part of the hot catalyst flowing up from elutriator 111, around the cracking reactor 109 via line 130 to the regenerator. This facilitates operating the cracking reactor at a temperature lower than that in the coking zone. The relatively coarse coke particles, preheated on contact with the regenerated catalyst, flow down through mixing section 111 while being stripped free of catalyst particles and are eventually withdrawn downwardly through standpipe 102 for mixing with fresh feed as previously described. Since sharp separation between the relatively fine catalyst particles and the coke in mixing zone 111 is desirable, maintenance of proper coke size in the system can be obtained by elutriation, screening, selective cyclone action or the like. For instance, this can be done by locating a cyclone 126 in some or even in all openings of the reactor grid 110 and by withdrawing the separated coke fines from the system through cyclone dip leg 127, or by the use of separate vessels for the coker and regenerator, cyclones being installed in the exit from the coker vessel. Likewise, coke particles grown too large for easy fluidization should be removed

7 from the system at least periodically, or with the product coke.

Likewise, where catalyst particles tend to stick to the coke in the heat transfer mixer 111 so that they would be eventually rejected from the system along with the product coke, further modification of the system may be desirable. For example, the difficulty can be overcome by mixing the coke as it leaves the coking bed with hot recycle coke and then providing sufficient holding time to dry the coke in an intermediate zone before it contacts the hot catalyst in the heat transfer zone 111; and stripping steam can be added to assist the operation.

Referring back to grid 110 which supports the catalyst bed in the cracking section 109 above the dilute phase of the coking section 105, it is important that the pressure drop across the grid be such as to cause the desired upward flow of catalyst from the mixer-elutriator 111 to the 10 catalyst bed 112 while preventing flow of catalyst to the coker bed 107 through wall opening 125. The required pressure drop will usually range between about 1 and 5 or 10 pounds per square inch and must be at least enough to offset the 15 differential between the hydrostatic pressure exerted by the relatively dense upward stream of catalyst fines suspended in steam in the upper portion of the mixer-elutriator section 111 of the reactor vessel, the apparent density of this phase being between about 10 and 40 lbs. per cu. ft., and, on the other hand, the adjacent dilute phase 20 existing above level 108 of the fluid coker bed 107. In general, the velocity through the openings in grid 110 should be maintained in the proper range 25 to give the required pressure drop so as to compensate for the lower density in the dilute phase above level 108 compared to that in the upper part of zone 111.

In the operation of this system, the temperature at the coke-catalyst mix point is regulated to give the desired heat balance. The coke circulation rate is controlled by the valve in line 102 to supply the desired heat to coking zone 105, and the catalyst rate will be fixed by the heat released in the regenerator and the difference between the temperatures in lines 115 and 123, although auxiliary cooling (or heating) means may be provided. Also, additional flexibility is possible by flowing part of the catalyst through bypass line 130. These controls allow operation over a wide range of coker, cracking, and regeneration temperatures, and provide flexibility in catalyst/oil ratio.

Fig. 3 illustrates still another embodiment of the invention. In operating this system a liquid residuum of the type previously described, pre-heated to about 300° to 800° F. may be supplied through line 142. Hot inert solids, specifically coke having a particle size of about 100 to 500 microns may be added from standpipe 144 at a temperature of about 900 to 1100° F. in an amount of about 700 to 7,000 lbs./barrel. By this addition of hot coke the temperature of the feed may be raised to about 800 to 1000° F. where-by the more volatile components of the feed are more or less completely vaporized without, however, being converted to naphtha and lighter products in any substantial degree. The less volatile components of the feed are deposited on the coke particles during their travel through line 143 and before they enter the reactor 146. In particular it is desirable to make line 143 sufficiently long to allow for a residence time therein of about 0.5 to 5 seconds so that substantially all

5 inorganic salts and other contaminants as well as a large proportion of carbon from the asphaltenes and other carbon forming constituents of the feed are deposited on the coke particles and the resulting carbonaceous deposit is sufficiently dried to avoid undue stickiness of the coke particles after they enter reactor 146.

10 The resulting dispersion of coke in hydrocarbons may enter reactor 146 through distributing grid 148 to form above the grid a dense turbulent fluidized bed or mass M₁₄₆ of the type specified earlier with reference to the reactors of Figures 1 and 2. About 700 to 5,000 lbs. of hot regenerated catalyst per barrel of feed may be supplied from standpipe 150 as will appear hereafter. As in the previously described examples, this catalyst has a particle distribution range below the range of the above-described coke particles, for instance, the catalyst may have a particle size up to about 80 microns and must be readily entrainable at the fluidization conditions of reactor 146. Mass M₁₄₆ is maintained at a temperature of about 900 to 1100° F. conducive to the desired catalytic cracking operation and may be composed of a highly active silica-alumina composite or other known cracking catalyst.

15 Reactor 146 may be provided with an elutriation well 152 into the bottom of which an elutriation gas such as steam or a light hydrocarbon gas is admitted via line 154. Preferably the elutriation well is a small-diameter vertical section which extends downwardly from a point just below dense bed level L₁₄₆ so as to be in open communication with dense, fluidized bed M₁₄₆ and is preferably filled with a packing of bodies of non-fluidizable size, such as Raschig rings or the like, having interstices which permit percolation of the fluidized solids within the packing. The elutriation gas may be supplied via line 154 at a rate sufficient to elutriate from packed section 152 substantially all the catalyst so that coke particles practically free of catalyst may be withdrawn via standpipe 144 and supplied to line 143 in the manner and for the purpose described above. Any desired portion of the withdrawn coke may be drawn off standpipe 144 via line 156 for the removal of net product coke, together with the contaminants deposited thereon. Purified or make-up solids may be supplied to the system via line 158, as for example seed coke, or make-up catalyst.

20 The catalyst which may contain up to about 3 wt. per cent of coke is readily entrained by the product vapors and elutriation gas and carried in the form of a dilute suspension overhead from mass M₁₄₆ through line 160 into separator 162 from which product vapors may be passed to recovery via line 164. Separated catalyst, preferably stripped of hydrocarbons by injection of an inert gas such as steam through one or more taps t to a stripping zone may be supplied via line 166 to a lower portion of catalyst bed M₁₆₈ in regenerator 168. Simultaneously, air is blown into regenerator 168 through line 170 and grid 172 at conditions suitable to maintain the catalyst mass M₁₆₈ in a dense, turbulent condition at a temperature of about 1000 to 1200° F. by combustion of coke deposits in a manner well known per se and heretofore outlined in connection with the catalyst regenerators of Figs. 1 and 2. Flue gases and entrained catalyst may pass into cyclone 174 from which separated catalyst fines may be returned via dip leg 176 or discarded via line 178, flue gases being withdrawn via line 180. Make-up catalyst may be added

through line 181 and hot regenerated catalyst returned to reactor 146 through standpipe 150 as described above.

Having described specific embodiments of the invention as well as suitable methods of operation, it will be understood that this was done for purposes of illustration rather than limitation. For instance, beyond the scope of the specific examples given, the invention is broadly applicable to the treatment of heavy residual crude stocks, and offers certain advantages even with lighter stocks such as cycle stocks or any other oils which tend to deposit solid residues such as coke when heated or cracked. Such stocks may be reduced crudes obtained by atmospheric or vacuum distillation and may represent the bottom 2 to 25 vol. per cent of the virgin crude distilled, or the invention may be applied to heavy clarified oil obtained from catalytic cracking, to tar from visbreaking operations and to other similar stocks or pitches unsuited for direct feeding to a catalytic cracking zone because of their excessive carbon-forming and/or other catalyst contaminating propensities. Prior to feeding to the coker, such heavy feed stocks are usually preheated to temperatures ranging from 200 to 1000° F., preferably 600 to 800° F., and the viscosity of the stocks may be further reduced by dilution with naphtha or other light hydrocarbons. Moreover, the hydrocarbon feed may also be diluted in the reaction zones with steam, recycle gas or other inert gases in amounts up to about 500 to 5000 cu. ft. per barrel since such diluent gas offers a convenient means for maintaining the desired fluidizing and/or elutriating velocities in the pertinent zones. Such linear gas velocities may typically range between about 5 and 50 feet per second in transfer lines carrying a dilute suspension of solid particles in vapor, as in line 31 of Fig. 1, line 104 of Fig. 2 and lines 143 and 160 of Fig. 3. On the other hand in conversion zones containing a dense fluid bed of solids, such as in beds 3, 7 and 17 of Fig. 1, the desired linear gas velocity may range between about 0.5 to 5 or 10 feet per second so as to establish apparent bed densities of about 10 to 50 lbs. per cu. ft., and densities between about 0.01 to 5 or 10 lbs. per cu. ft. in the disperse phases above the dense beds. In elutriation zones such as zone 20 of Fig. 1, zone 111 of Fig. 2 or zone 152 of Fig. 3 the velocity must be further chosen so as to accomplish the desired separation of fine and coarse particles, the optimum elutriation velocity in each case depending on the particle size and density, as well as size and density differential of the two solid fractions as is well known per se.

The inert contact solids used in the coker are preferably coarse coke particles ranging in size from about 100 to 300 or 500 microns, though other inert solids such as sand, spent clays, pumice and the like may similarly be used as seeds for the conversion coke if a coke product of high ash content can be tolerated. Moreover, particularly in starting up the operation at a time when no coke is available, the use in the coker of some of the aforementioned inorganic seed solids, or even of spent, carbon-contaminated catalyst may be necessary and desirable. Also, finer coke particles may be used in alternative systems where the coke is to constitute the more readily entrainable solid phase as hereafter described at somewhat greater length.

The inert solids are held up in the primary

coking zone such as bed 2 of Fig. 1 for an average residence time ranging from about 1 to 150 minutes so as to provide sufficient surface area for the deposition of a readily cokable residuum film around the solid particles. The ratio of residuum feed to solids in the coker zone is maintained at a value preferably not in excess of about 1 wt./wt./hr., when the reactor is operated at about 900° F., or 3 wt./wt./hr. at 1000° F. reactor temperatures, as otherwise the wet coke particles tend to stick excessively and prevent proper fluidization. Where the primary coking zone is in the transfer line, as in line 104 of Fig. 2 or in line 143 of Fig. 3, residuum feed stock and hot coke particles are mixed therein in a weight ratio between about 1 and 10 parts of coke per part of oil.

In the mixing zones, the coke or other inert solids are reheated to the desired temperature by mixing with about 0.2 to 2 parts of hot regenerated catalyst per part of inerts, the optimum ratio in each case obviously depending on the temperature of the regenerated catalyst as well as on the desired conversion temperatures, oil preheat temperature, etc.

The contact solids in the catalytic cracking zone may be a catalyst such as activated clay, activated alumina, activated composites of silica with alumina or magnesia or boria, activated carbon, or other conventional cracking catalyst. The particle size of the catalyst may range between 0 to 100, or preferably between 20 and 80 microns and, as mentioned earlier, the catalyst particles are preferably smaller than the inert particles by a sufficient size differential to permit ready separation of the two by elutriation. The apparent densities and gas velocities prevailing in the various catalyst phases are substantially within the same limits as given above with reference to the coker solids, though it will be understood that in any given system the minimum fluidization velocity required in a zone containing relatively small catalyst particles as the only solids may be substantially lower than the minimum gas velocity required for the fluidization of the relatively coarser coker solids.

It may also be noted that while the preferred embodiments of the invention use catalyst in a form more readily entrainable than the inert solids as heretofore described, various advantages may also be secured by the reverse arrangement according to which the inert solids may be the more readily entrainable material. One particular advantage of the latter arrangement is that loss of catalyst due to adhesion to wet coke and subsequent rejection of the adhered catalyst with the coke product can thus be further minimized, albeit at the expense of somewhat increased requirements for regenerator capacity caused by greater contamination of the spent catalyst by the adhering coke fines. If desired, the systems heretofore described and illustrated may be readily adapted to this reverse type of operation in a manner obvious to those skilled in the art so that, using the system of Fig. 3 as an example, the fine inert solids entrained overhead from reactor 146 with the product vapors would, after separation in a cyclone or the like, be mixed again with the incoming feed stock in a transfer line such as line 143 leading to the reactor while spent catalyst withdrawn through elutriator standpipe 144 would be passed through a separate transfer line into the bottom of a catalyst regenerator such as vessel 168 and finally

11

returned therefrom through standpipe 150 to the reactor.

Reaction conditions may include coking temperatures of about 800 to 1200° F., catalytic cracking temperatures of about 800 to 1000° F. and catalyst regeneration temperatures of about 1000 to 1200 or 1300° F., depending on the nature of the catalyst used. Of course, the regenerator temperature and the rate of circulation of catalyst and coke to the mixing zone where the inert 10 solids are reheated to the desired coking temperature by direct heat exchange with the catalyst before separation and recycling to the conversion zones, are so adjusted as to give the intended temperature conditions both in the coking zones and the catalytic cracking zones.

Having given a full description of the invention and of the manner of using it, the invention is particularly pointed out and distinctly claimed in the appended claims.

We claim:

1. A process for converting a residual petroleum feed stock boiling predominantly above 900° F. into lighter products and coke which comprises introducing the residual stock into a primary coking zone wherein coke particles of a size between 100 and 500 microns are maintained at a temperature between about 800 and 1100° F. as a dense fluidized bed with a less dense phase thereabove, and wherein the petroleum stock is vaporized and partially coked without substantial conversion to naphtha and lighter products, passing the resulting petroleum vapors upwardly through a cracking zone maintained at about 900 to 1100° F. and containing a dense fluidized bed of cracking catalyst ranging in particle size up to about 100 microns with a less dense phase above said bed, recovering cracked vapor products from the cracking zone, passing spent catalyst from the cracking zone to a regeneration zone maintained at a temperature between about 1000 and 1300° F. through which an oxygen-containing gas is passed in an upward direction at a rate sufficient to maintain the catalyst particles as a dense fluidized mass while burning off deposited carbon, overflowing the coke particles containing a wet coat of partially coked feed from the aforesaid primary coking zone to at least one secondary coking zone wherein the coke particles are maintained at a temperature above 800° F. as a dense fluidized mass by upward passage of a dry inert gas therethrough, recovering dry net coke product from the secondary coking zone, passing a portion of the dried coke from the secondary coking zone to a mixing zone, also passing a portion of catalyst at a temperature above 1100° F. from the regeneration zone to the mixing zone and there intimately mixing it with the dried coke, passing an inert gas upwardly through the resulting particle mixture in the mixing zone at a rate above the minimum fluidization rate of the coke and at a rate sufficient to strip and entrain the relatively fine catalyst particles from the mixture, returning the entrained catalyst particles from the mixing zone to the conversion process, withdrawing catalyst-free, reheated coke particles from the bottom of the mixing zone and returning the reheated coke to the primary coking zone.

2. A process according to claim 1 wherein the secondary coking zone, the primary coking zone and the catalytic cracking zone are superimposed above each other in the sequence recited.

3. A process according to claim 1 wherein some

12

of the reheated coke withdrawn from the mixing zone is returned to each of the coking zones and wherein the secondary coking zone is maintained at a temperature between 1000 and 1200° F. and substantially higher than the temperature of the primary coking zone.

4. A process for converting a residual hydrocarbon feed characterized by a Conradson carbon value in excess of 5 which comprises preheating the feed to a temperature between 600 and 800° F., mixing the feed with coke particles ranging in size between about 100 and 300 microns and heated to a temperature between about 300 and 1200° F. to form a dilute suspension of coke in hydrocarbon vapors, passing the resulting suspension at a temperature of about 800 to 1100° F. through an elongated and constricted primary coking zone at a superficial gas velocity of about 5 to 50 feet per second to a secondary coking zone of wider diameter wherein the upward gas velocity is within the range between 0.5 and 4 feet per second and wherein the suspended coke particles are accordingly maintained as a dense, turbulent, fluidized mass, withdrawing the resulting hydrocarbon vapors from the secondary coking zone into and upwardly through a catalytic cracking zone superimposed thereabove, interposing a pressure drop of about 1/2 to 5 lbs./sq. in. in the path of the hydrocarbon vapors between the secondary coking zone and the cracking zone, contacting the hydrocarbon vapors with catalyst particles ranging in size between about 0 and 80 microns and maintained as a dense turbulent fluidized mass in the lower portion of the cracking zone at a temperature of about 900 to 1100° F., withdrawing cracked hydrocarbon vapors overhead from the cracking zone, withdrawing spent catalyst from the dense turbulent mass of the cracking zone and passing it to a regeneration zone where it is maintained as a dense, turbulent, fluidized mass and regenerated by upward passage of an oxygen-containing gas therethrough at a temperature between 1000 and 1200° F., withdrawing hot catalyst from the regeneration zone and passing it to a lower portion of a mixing zone located adjacent to the secondary coking zone and below the cracking zone, overflowing coke particles from the dense turbulent mass of the secondary coking zone into an upper portion of the mixing zone where the coke becomes reheated by countercurrent contact with the regenerated catalyst, introducing an inert gas near the bottom of the mixing zone at a rate sufficient to entrain the catalyst particles from the catalyst-coke mixture into the superimposed cracking zone, withdrawing reheated coke particles from the bottom portion of the mixing zone, and mixing the withdrawn coke with incoming feed.

5. A process for converting heavy hydrocarbons which comprises mixing a heavy hydrocarbon feed with coke particles ranging in size between about 100 and 300 microns and heated to about 900 to 1200° F. to form a dilute suspension of oil-coated coke particles in hydrocarbon vapors, passing the resulting suspension through a constricted elongated coking zone at a temperature between 800 and 1100° F. at a rate of 5 to 50 feet per second for a time of about 0.5 to 5 seconds and thereby coking the oily coat deposited on the coke particles, thereafter introducing the suspension into a cracking zone of relatively large cross-section wherein the upward velocity of the hydrocarbon vapors is reduced to about 0.5 to 5 feet per second and wherein the introduced suspension becomes mixed with cracking catalyst

13

particles ranging in size between 0 and 80 microns and the catalyst-coke mixture is maintained therein as a dense, turbulent bed having an upper level with a less dense catalyst suspension thereabove, segregating a portion of the said mixture in an elutriation zone communicating with an upper portion of the dense turbulent bed within the cracking zone, passing an inert gas upwardly through the elutriation zone at such a rate as to strip the catalyst particles out of the catalyst-coke mixture into the relatively less dense suspension above the turbulent bed of the cracking zone, withdrawing the relatively less dense suspension of catalyst in cracked hydrocarbon vapors overhead from the cracking zone, 15 mechanically separating the catalyst particles from the hydrocarbon vapors in the withdrawn suspension, recovering the separated hydrocarbons, passing the separated catalyst to a regeneration zone wherein the catalyst particles are 20

14

maintained as a dense turbulent mass by upward passage of an oxygen-containing gas, returning hot regenerated catalyst to the dense turbulent mixture of coke particles and catalyst within the cracking zone and thereby supplying heat to the mixture, withdrawing coke particles from the bottom of the elutriation zone, and mixing the withdraw coke particles with incoming feed.
